(57) CLAIM

The ornamental design for a rifle weapon, as shown and described.

DESCRIPTION

The patent or application file contains at least one drawing executed in color. Copies of this patent or patent application publication with color drawing(s) will be provided by the Office upon request and payment of the necessary fee.

1. Rifle [weapon]

FIG. 1.1 is a right side view of a rifle weapon showing our new design;

FIG. 1.2 is a perspective view from above and to the left side thereof;

FIG. 1.3 is a perspective view from above and to the right side thereof;

FIG. 1.4 is a front elevational view thereof;

FIG. 1.5 is a rear elevational view thereof;

FIG. 1.6 is a top plan view thereof; and

FIG. 1.7 is a bottom plan view thereof.

The portion of the design shown in the color red is for the purpose of illustrating portions of the rifle weapon that forms no part of the claimed design.
